US00D948052S

(12) **United States Design Patent** (10) Patent No.: **US D948,052 S**
(45) Date of Patent: ** Apr. 5, 2022

(54) **PART OF SPINAL FUSION CAGE**

(71) Applicant: **L&K Biomed Co., Ltd.**, Yongin-si (KR)

(72) Inventor: **Gook Jin Kang**, Seoul (KR)

(**) Term: **15 Years**

(21) Appl. No.: **35/510,470**

(22) Filed: **Mar. 27, 2020**

(80) **Hague Agreement Data**

Int. Filing Date: **Mar. 27, 2020**

Int. Reg. No.: **DM/209461**

Int. Reg. Date: **Mar. 27, 2020**

Int. Reg. Pub. Date: **Oct. 2, 2020**

(30) **Foreign Application Priority Data**

Oct. 7, 2019 (KR) 30-2019-0047893

(51) LOC (13) Cl. **24-03**

(52) U.S. Cl.

USPC **D24/155**

(58) **Field of Classification Search**

USPC D24/155; D21/478-480, 484

CPC A61F 2/44

See application file for complete search history.

Primary Examiner — Darcey E Gottschalk

(57) **CLAIM**

The ornamental design for a part of spinal fusion cage, as shown and described.

DESCRIPTION

1. Part of spinal fusion cage

1.1 : Perspective

1.2 : Front

1.3 : Back

1.4 : Left

1.5 : Right

1.6 : Top

1.7 : Bottom

1.8 : Reference view of state of use

1.9 : Reference view of state of use

In the reproductions, the evenly-spaced broken lines show portions of a spinal fusion cage that form no part of the claim; the dash-dot-dash lines represent boundaries of the claimed design that form no part thereof.

1 Claim, 9 Drawing Sheets
